UNITED STATES PATENT OFFICE

JOHN CHRISTOPHER EHLENFELD, OF DANVILLE, ILLINOIS

SIGN

Application filed November 11, 1930. Serial No. 494,963.

This invention aims to provide novel means whereby, through the instrumentality of wind force, pointers may be made to move up and down, the pointers being arranged in operative relation to a sign or being disposed otherwise, as preferred by the operator or manufacturer.

It is within the province of the disclosure to improve generally and to enhance the utility of devices of that type to which the invention appertains.

With the above and other objects in view, which will appear as the descriptions proceed, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows in perspective, a device constructed in accordance with the invention;

Figure 2 is a vertical sectional view of a portion of the structure shown in Figure 1, parts being broken away;

Figure 3 is a section on the line 3—3 of Figure 2;

Figure 4 is a section on the line 4—4 of Figure 2;

Figure 5 is a section on the line 5—5 of Figure 2;

Figure 6 is a perspective view showing a modification;

Figure 7 is a perspective disclosing another modification of the invention;

Figure 8 is an elevation of the device that appears in Figure 7, parts being broken away and parts being in elevation;

Figure 9 is an elevation showing a further modification;

Figure 10 is an elevation illustrating another modification;

Figure 11 is a perspective view of the shaft and attendant parts as used in Figure 10;

Figure 12 is an elevation disclosing a still

further modification of the invention, parts being broken away;

Figure 13 is an elevation showing a further modification;

Figure 14 is a fragmental elevation taken at right angles to the showing of Figure 13;

Figure 15 is a top plan wherein parts are in section.

In carrying out the invention as disclosed in Figures 1 to 5, there is provided a support, which may be of any desired construction. The support may embody vertical posts 1, made of pipe, each post embodying a lower section 2 seated in a concrete foundation 3, although some other method might be provided for mounting the posts at their lower ends. The lower sections 2 of the posts 1 are connected detachably, by couplings 4, with upper sections 5, which, like the lower sections 2 are hollow.

At their upper ends, the upper sections 5 of the posts are split vertically, and oppositely disposed portions of the material freed in the splitting are turned outwardly, in a horizontal direction, to form oppositely extended bearings 6. The remaining portions of the material freed as aforesaid by the splitting, stand vertically to form fingers 7 carrying a securing element 8, such as a cotter pin.

A shaft 9, which may be of a piece of pipe, is mounted to rock on the oppositely extended bearings 6, between the fingers 7. The shaft 9 is prevented from jumping out from between the fingers 7, by the securing elements 8 or cotter pins 8.

Caps 10 are mounted on the ends of the shaft 9, and, cooperating with the outer bearings 6, limit the longitudinal movement of the shaft 9 as it rocks upon the bearings 6.

A plug 12 which may be made of cement or anything else, is mounted in each of the upper sections 5 of the posts, near to the upper ends of the posts. On top of each plug 12 within the post sections 5 is located an absorbent member 14 which may be made of waste. The absorbent member 14 is kept soaked with oil, and bears against the shaft 9, to lubricate the shaft. The numeral 15 marks a depending sign, which may be of any

desired construction. The sign 15 is held on the shaft 8 by end straps 16 of metal.

A cross arm 17 is mounted in the shaft 9 rigidly, at a point near to one end of the shaft. On one end of the cross arm 17, a counter weight 18 is held for adjustment longitudinally of the cross arm, by means of a set screw 19 shown in Figure 4. To the opposite end of the cross arm 17 is connected a downwardly extended flexible element 20, the lower end of the flexible element being connected to a pointer 21, located at one end of the sign 15.

Passing to a specific description of the pointer 21, and noting Figure 2 in connection with Figure 3, the reader will note that the pointer embodies a two-part fork 22, the constituent members of which are secured on opposite sides of a hand 23 which constitutes the indicating portion of the pointer 21.

Any suitable element may be substituted for the hand 23. Display plates 24 are secured to the spaced portions of the fork 22. Holes 25 are formed in the display plate 24 and in the spaced portions of the fork 22, so that the operator can attach other display elements, if he desires. Figure 4 shows that the lower end of the flexible connection 22 is joined at 26 to the shank of the fork 22 and to the hand 23, inwardly of one of the posts 1.

The upper section 5 of one post carries a rivet 27 or the like, on which is supported a plug 28 of cement or any other suitable material. An absorbent member 29 is located in the upper section 5 of the said post 1 and is supported by the plug 28. The said upper section 5 has an oil hole 30 through which a lubricant may be inserted, to keep the absorbent member 29 well saturated. A pivot element 31 extends through the absorbent member 29 and is mounted in the said upper sections 5. The pivot element 31 passes through the spaced portions of the fork 22 and through the plates 25 and thus the pointer 21 is mounted intermediate its ends for vertical swinging movement on one of the posts 1.

In practical operation, the wind causes the sign 15 to swing to and fro, and the shaft 9 is rocked. The cross arm 17 operates the flexible element 20, the pointer 21 is swung upwardly and downwardly on its pivotal mounting 31, and the pointer, thus, attracts attention to the sign 15.

Some may not wish to use a pipe or rod to make the shaft 9, and under such circumstances, recourse is had to the structure delineated in Figure 6 of the drawings. In that figure, the post 32 is provided at its upper end with diverging fingers 33 forming a V-shaped seat 34. The shaft 35 is in the form of a T-bar, the horizontal flange 36 of which is cut away to form a shoulder 37, and to form a projecting end 38 in the downwardly extended vertical flange 39 of the T-bar or shaft. The end 38 of the shaft extends through a

slot 40 formed in a washer 42 that abuts against the shoulder 37, the washer 42 cooperating with the fingers 33 to prevent appreciable lengthwise movement of the shaft 35. The end 38 of the shaft has a knife edge 41 which rocks in the V-shaped seat 34 and affords a very delicate bearing for the shaft 35, so that the said shaft can rock easily, it being understood that the shaft 35 is supplied with a sign, like the sign 15, although the structure shown in Figure 6 is applicable to many other forms of the invention.

In the form shown in Figures 7 and 8, there appears a building 43 having a doorway 44 and windows 45. The support for the swinging sign is in the form of an angle bracket 46, secured to the building 43 adjacent to one of the windows 45, or elsewhere, and having a depending end 47, the angle bracket being sustained by guys 48 wherever necessary or desirable.

U-shaped hangers 49 are suspended from the horizontal part of the angle bracket 46 and have cups 50 at their lower ends, these cups being adapted to receive an absorbent packing 51 which, being well soaked with oil, lubricates a shaft 52 that rocks in the hangers 49.

The shaft 52 carries a sign 53. The sign 53 is shown in the form of a plate, but the manufacturer can provide any desired sort of sign. The shaft 52 carries a cross arm 54 like the cross arm 17. The pointer 56 may be of any preferred construction. The pointer hereinbefore described, and shown in detail in Figures 2 and 3 may be used. The pointer 56 is pivotally mounted at 57 on the depending end 47 of the angle bracket 46. The hand of the pointer is shown at 58. A flexible element 55 is connected to the hand 58 and to the cross arm 54. A clapper bell 59 is mounted on the shaft 52, near to the arm 54.

In practical operation, the wind swings the sign 53 and rocks the shaft 52, the bell 59 being made to sound. The cross arm 54 and the flexible element 55 swing the pointer 56 up and down on its pivotal mounting 57, the pointer being located near to the end of the sign 53 and serving to attract attention to the sign, as hereinbefore explained in connection with the form which is depicted in Figure 1.

In Figure 9 there is shown a support 60 carrying an angle bracket 61 having a depending end 62 long enough to extend down to the ground, although the part 62 need be no longer than the part 47 of Figure 8.

Hangers 63 of the kind shown at 49 in Figure 8 are employed, and have lubricating cups 64. The shaft 65 is mounted to rock in the hangers 63 and carries a downwardly extended sign 66 of any desired construction.

A cross arm 67 and another cross arm 68 are mounted on the shaft 61. These cross arms may be provided with the weight 18 of Figure 1, if desired, and the same observation

5 holds true with respect to the cross arm 54 of Figure 8. A flexible element 69 connects the cross arm 67 with a rocking chair 71 or other object carried by a display plate 70, the rocking chair being pivotally mounted at 72 on a bracket 73 carried by the support 60. The cross arm 68 is connected by a flexible element 74, with a pointer 75 pivotally mounted at 76 on the depending end 62 of the angle bracket 61, the pointer 75 being of the construction shown in Figure 2, if the operator desires. Any kind of an object, of course, can be mounted on the plate 70 in place of the rocking chair 71.

15 In Figures 10 and 11 there is shown a support in the form of a building 77 having windows 78 between which is located a doorway 79.

20 A horizontal bracket 80 is secured to the building 77 above the doorway 79. Hangers 81, provided with lubricating cups 82, are mounted on the bracket 80. A horizontal shaft 83 rocks in the hangers 81 and carries a sign 84.

25 A long cross arm 85 is secured intermediate its ends to the shaft 83 and extends over the windows 78. Flexible elements 86 extend downwardly from the ends of the cross arm 85 and are connected to pointers 87 carrying supplemental signs 90 of any preferred description. The pointers 87 are pivotally mounted at 88 on brackets 89 carried by the building. The pointers 87 direct attention to the doorway 79 and also move vertically in 35 front of the windows 78.

30 In practical operation, the wind acts on the sign 84 and rocks the shaft 83. The cross arm 85 swings up and down at its ends, and the flexible elements swing the pointers 87 up and down.

35 In Figure 12 there is shown a shaft 100, which may be supported for rocking movement in any of the ways hereinbefore described. The shaft 100 carries a sign 101. A cross arm 103 is mounted on the shaft 100. The cross arm 103, and all of the cross arms referred to in this specification, may be supplied with the adjustable counterweight 18 of Figure 4.

40 The numeral 104 designates a rigidly mounted figure having a head 105 provided with a mouth 111 and with a movable jaw 106 which is pivotally mounted at 107 on the head 105. The figure 104 has an arm 108 which is pivotally mounted at 109, intermediate its ends, on the figure 104, the arm 108 and the jaw 106 having vertical movement. The arm 108 may terminate, at its outer end, 45 in a hand 114 carrying an object 110, supposed to be subject to mastication, such as a plug of chewing tobacco, a piece of candy, a hot dog or the like. A flexible element 112 is connected to the inner end of the arm 108 and to the jaw 106. A flexible element 113 is

connected to the jaw 106 and to the cross arm 103.

45 In practical operation, the sign 101 is actuated by the wind, and operates the shaft 100, rocking movement being imparted to the shaft. The arm 103 and the flexible element 113 cause the jaw 106 to move up and down. The flexible element 112 will cause the arm 108 to swing up and down, the object 110 being inserted into the mouth 111, and being withdrawn therefrom, in synchronism with the vertical movement of the jaw 106, the jaw moving downwardly as the object 110 is inserted into the mouth 111, the jaw moving upwardly as the object 110 is withdrawn from the mouth 111.

50 In Figures 13, 14 and 15, there is shown a support 224, which may be one of the posts 1 of Figure 1. On the support 224, a horizontal shaft 225 is mounted for rocking movement. A sign 226 is secured at 227 to the shaft 225. The shaft 225 has a cross arm 228 upon which a weight 229 is adjustably mounted, as hereinbefore explained.

55 A bracket 230, in the form of a horizontal rod, projects from a post or support 224, and forms part thereof. A vertical U-shaped guide 231 is secured at its lower end, as shown at 232 in Figure 13, to the bracket or rod 230.

60 A pair of upper jaws 233, made to represent human teeth, are provided, and have side arms 234 which are pivotally mounted at their inner ends on the rod 230. Lower jaws 235 are supplied and have side arms 236. The side arms 236 and the side arms 234 are 65 crossed on each other and are pivotally connected at 237, where they cross. The inner ends of the side arms 236 of the lower jaws 234 are pivotally mounted on a connection 238, in the form of a rigid rod, mounted to move vertically in the U-shaped guide 231. A flexible element 239 is connected to the rod 238 and to the arm 226 on the shaft 225.

65 In practical operation, when the sign 226 swings in the wind, the shaft 225 is rocked, and the cross arm 228 causes the flexible element 239 to move vertically, the rod 238 moving vertically in the guide 231. As the rod 238 moves up and down in the guide 231, a peculiar movement is given to the jaws 233 and 235. The jaws 235 and 233 not only open and close with respect to each other, but they have a bodily up and down movement about the pivot point represented by the rod 230. Moreover, as the jaws close and open, they have a lateral or horizontal movement in the direction of the arrows A, in Figure 14, and the general appearance is that the jaws are jumping out and snapping at something as they close.

70 Having thus described the invention, what is claimed is:

75 1. In an advertising device, a shaft supported for rocking movement, a wind-actuated sign on the shaft, a pointer mounted for

swinging movement, and an operative connection between the shaft and the pointer, whereby the pointer will be moved by the sign when the sign is actuated by the wind.

5 2. In an advertising device, a shaft supported for rocking movement, a hanging sign carried by the shaft, a cross arm on the shaft, a movably mounted pointer, and a connection between the arm and the pointer where-
10 by the pointer will be operated when the sign is wind-actuated.

15 3. In an advertising device, a tubular post, a shaft journaled on the post, a sign carried by the shaft and wind-actuated to rock the shaft, a pointer, a pivot element carrying the pointer and mounted to move in the post, lubricators within the posts, one lubricator co-operating with the shaft and the other lubricator cooperating with the pivot element and
20 an operative connection between the shaft and the pointer, whereby the pointer will be moved by the sign when the sign is actuated by the wind.

25 4. In a device of the class described, a support, an angle bracket carried by the support and including a depending end, a pointer mounted to move on the depending end of the angle bracket, a shaft supported for rocking movement on the angle bracket, a wind-actuated sign carried by the shaft, and an operative connection between the shaft and the pointer.

30 5. In a device of the class described, a support, a shaft carried for rocking movement by the support, a wind-actuated sign on the shaft, a cross arm connected to the shaft, spaced pointers mounted for swinging movement and located on opposite sides of the shaft, and connections between the pointers
35 and the ends of the shaft.

40 In testimony that I claim the foregoing as my own, I have hereto affixed my signature.

JOHN CHRISTOPHER EHLENFELD.
